ELECTRIC FLATIRON

Jose Antonio Guerra, San Salvador, El Salvador

Application March 23, 1950, Serial No. 151,400

2 Claims. (Cl. 219—25)

1

The present invention relates to an electric flat iron and more particularly to an electric flat iron in which the electric current supplied to the iron heating element is more efficiently utilized.

In conventional electric flat irons, such as those now commercially available, an electrical resistance heating element is tightly compressed between a pair of heavy masses of metal which constitute the body of the iron and give it a requisite pressing weight. As a result, the heat developed by the heating element is transmitted and dissipated throughout the mass of the heavy metal elements. This dissipation of heat has resulted in the consumption of a relatively large amount of electric energy for a relatively small effective heat output.

The device of the present invention provides a novel type of electric flat iron in which the resistance heating element is compressed between two relatively thin plates, the lower plate being of steel or other metal having relatively good heat transfer characteristics so that it may serve as the sole or pressing plate of the iron. The upper plate is preferably formed of metal having a relatively low specific heat coefficient, preferably on the order of less than about 0.07 calories per gram at iron operating temperatures, which may attain a maximum of about 500-600° F. Suitable metals for such use are lead, platinum, silver, tin, and tungsten.

The advantages of employing such materials having low specific heat coefficients will be appreciated from the fact that a much smaller heat input is necessary to raise these materials to the temperature of the heating element, thereby preventing the loss of heat by absorption in the upper plate. Consequently, a larger proportion of the heat introduced into the heating element is available for use at the sole plate and great economy in operation results.

In addition, the necessary weight for effective pressing action of the iron is obtained by means of a second low specific heat member disposed out of thermal contact with either the heating element or the upper and lower plates in contact therewith. The thermal insulation of the weight may be obtained either by the employment of thermal insulating material or by an air gap, or preferably by a combination of these insulating media. In this manner, the distribution of the heat furnished to the heating element is confined to a relatively small portion of the iron and not to the weight mass of the iron.

It is, therefore, an important object of the present invention to provide a novel form of an electric flat iron which efficiently utilizes electrical thermal energy supplied thereto.

Another important object of the present invention is to provide an electrical flat iron including an electrical resistant heating element in thermal proximity to a sole plate and to a pressure plate having a low specific heat coefficient, whereby a great proportion of the electrical thermal energy supplied to the heating element is transmitted to the sole plate with small heat loss through the pressure plate.

It is a further object of the present invention to provide an improved electric flat iron including a heating element confined under pressure between a sole plate and a pressure plate in efficient thermal proximity and an additional weight in insulated thermal relation to the heating element and the pressure plate, said weight and said pressure plate being formed of materials having low specific heat coefficients at the operating temperature of the iron to prevent the loss of thermal energy.

Still another important object of the present invention is to provide an electric flat iron comprising a heating element in effective thermal relation to a sole plate and means having a low specific heat coefficient for confining thermal energy from the heating element to the sole plate, thereby obtaining effective use of the heat energy supplied to the heating element.

Other and further important objects of this invention will be apparent from the disclosures in the specification and the accompanying drawings.

On the drawings:

Figure 1 is a side elevational view, with parts broken away and in section, of an electric flat iron of the present invention;

Figure 2 is an exploded, sectional view with parts shown in elevation of the iron in Figure 1; and

Figure 3 is a sectional view with parts shown in elevation, taken along the plane III—III of Figure 1.

As shown on the drawings:

As shown in Figure 1, reference numeral 10 refers generally to an electric flat iron of the present invention, including a sole plate 11 having an upturned marginal flange, a pair of upstanding exteriorly threaded posts 13 secured, as by welding, to the interior surface of the sole plate 11 and projecting upwardly therebeyond, a sheet metal cover 14 having its lower free end bot-

tomed on the sole plate 11 in nested relation with the flange 12 and secured to the upper end of the posts 13 by suitable means, as by a nut 15, and a handle carried by the cover 14 and secured thereto by suitable means (not shown).

Enclosed within the housing defined by the cover 14 and the sole plate 11 and in pressure contact with the interior surface of the sole plate 11 is a heating element assembly 17, including electrical resistance wires 18 wrapped or coiled about a substantially flat core plate 19. The wires 18 have sufficient resistance to permit the passage of only that current necessary to heat the sole plate 11 to the desired operating temperature. An insulating plate 20 is disposed on each side of the core plate 19 in contact with the resistance heating wire 18. The plates 20 are substantially coextensive in both length and breadth with the sole plate 11, and each of the plates 19 and 20 is apertured, as at 21, along its length to receive the posts 13 without physically contacting the posts. The plates 20 are thus in contact with the resistance wire 18 and serve to electrically insulate the wires from the sole plate 11. The plates 19 and 20 are each made of an effective electrical insulating material; preferably of mica or the like.

Superimposed upon the heating element assembly 17 is a pressure plate 22 which is substantially coextensive with the plate 20 and which is apertured at 23 to receive the posts 13 without actual physical contact therewith. The pressure plate 22 is preferably made up of a material having a low specific heat coefficient, such as lead, tungsten, platinum, silver, or tin.

A sheet of thermal insulating material 24, such as asbestos and the like, is superimposed on the pressure plate 22 in surface contact therewith. Pressure is applied to the heating element assembly 17, the pressure plate 22, and the thermal insulating material 24 by means of separate washers 25 for each of the posts 13 and a nut 26 threaded on each of the posts 13 and urging the washers into surface contact with the insulating sheet 24. A second washer 27 is mounted upon each post 13 to overlie the nuts 26, and a relatively heavy weight 28 apertured at 29 to receive each of the posts without contacting same is superimposed on the washer 27, the weight 28 being preferably formed of material having a low specific heat coefficient as described in connection with the pressure plate 22. A third washer 30 and an additional nut 31 are positioned upon each of the posts 13 to overlie the weight 28 and to secure the same.

The structure of the present invention, as hereinbefore described, makes possible the attainment of several advantages over the prior art constructions. First, the means for applying pressure to the heating element assembly 17, thus urging the assembly into efficient thermal relation with the sole plate 11 facilitates the transmission of thermal energy from the heating assembly to the sole plate.

It will be noticed particularly from Figure 3 that the weight 28 is thermally insulated from the heating assembly 17 and the pressure plate 22 by both the insulating sheet material 24 and an air gap A. This air gap is substantially coextensive with both the longitudinally and transverse dimensions of the interior of the cover 14. Thermal insulation is further facilitated by the provision of enlarged apertures in the heating element assembly 17, the pressure plate 22, and the insulating sheet 24 so that each of these members

is out of direct physical contact with the posts 13. Thus, thermal insulation of the weight 28 aids in concentrating heat at the sole plate 11 and the heating element assembly 17 superimposed thereon.

The use of a pressure plate 22 and a weight 28 made of a low specific heat material results in a significant decrease in the consumption of electrical energy by these members. Since less heat is necessary to raise these members to the temperature which they must assume in operation of the iron, a maximum amount of heat is available at the sole 11, thereby increasing the efficiency of the iron.

As a result of the hereinbefore described features of the present invention, substantially all of the electrical thermal energy supplied by the heating element assembly 17 is available over a relatively small portion of the complete iron, namely, at the sole plate 11 and at the pressure plate 22. This concentration of heat at the sole plate is facilitated by the employment of low specific heat material for the pressure plate and the weight, pressure contact of the heating element with the sole plate, and the effective thermal insulation of the weight by both the air gap A and the insulation sheet 24. It will of course be realized that a thermostatic control may be employed in conjunction with the iron, as is conventional in the art, without necessitating any material change in the structure and/or features hereinbefore described.

It will be understood that modifications and variation may be effected without departing from the scope of the novel concepts of the present invention.

I claim as my invention:

1. In an electric flat iron, a sheet metal sole plate, an upstanding post secured to said sole plate, an electrical resistance heating element apertured to receive said post and in extended surface engagement with said sole plate, a pressure plate apertured to receive said post and in co-extensive surface engagement with said heating element, means on said post for urging said pressure plate toward said sole plate, thereby to press the heating element into intimate heat exchange contact with the sole plate, a ballast weight carried by said post in spaced relation above said pressure plate, said pressure plate and said ballast weight having specific heats substantially lower than said sole plate, whereby the flow of wasted heat to the pressure plate and the ballast weight is minimized, and a sheet of thermal insulation material interposed in the space between said weight and said pressure plate and of such thickness as to leave an insulating air space therebetween.

2. In an electric flat iron, a sheet metal sole plate, an upstanding threaded stud integral with said sole plate, a flat electrical resistance heating element apertured to receive said stud and in extended surface contact with said sole plate, a pressure plate apertured to receive said stud without contacting same and in co-extensive surface engagement with said heating element, a sheet of thermal insulation material coextensively overlying said pressure plate, means threaded on said stud and bearing against said insulating sheet for urging said pressure plate toward said sole plate for intimate heat exchange contact between said sole plate and said heating element, and a ballast weight apertured to receive said stud without contacting same and carried by said threaded means in spaced relation from said insulating

sheet to create an insulating air space between said sheet and said weight, said pressure plate and said ballast weight having specific heats substantially lower than said sole plate, whereby the flow of waste heat to the pressure plate and the ballast weight is minimized.

JOSE ANTONIO GUERRA.
